PISTON FOR INTERNAL COMBUSTION ENGINES

Waldemar Borrman and Albert Keune,
Badersleben, GermanyApplication October 19, 1937, Serial No. 169,788
In Germany March 27, 1937

7 Claims. (Cl. 309—7)

Pistons for internal combustion engines are not perfect for continuous working owing to corrosion, the possibility of seizing and to a seizing by fusion of the piston and piston rings, the more so as with these inconveniences an excessive consumption in fuel, oil and material is connected. It is also known, that wear of the pistons occurs much more rapidly on the piston head than on the piston body, as the latter is made resilient by a longitudinal slit. It has been proposed, to avoid wearing of the piston head by equipping it with closed rings, rigidly anchored in the piston body, or by fitting closed rings into the piston head and securely holding them by a cover plate. Rings for protecting against fusion and rings for protecting the piston edges have also been proposed. None of these constructions, however, brings the leading piston edge out of the range of the fire, so that the known protecting means cannot give a satisfactory result, the less so as they are not gas- and fireproof if protecting rings are employed constructed after the manner of piston rings. With the pistons of known type it is further not possible to keep the piston guide permanently under oil.

All these inconveniences are obviated by the invention. In the improved piston for internal combustion engines the piston protecting ring, which resiliently grips around the set-off piston head, forms at the same time an oil ring. The piston guiding begins below this protecting- and oil-ring, so that it is protected against the gases from combustion. The closure of the resilient piston protecting- and oil-ring is fire- and gas-proof even after the maximum wear, so that the full efficiency of the motor is ensured. To avoid hammering of the protecting ring, it may be securely held in position by a ring-shaped spring-insert. Whereas further by the special practical arrangement of the protecting- and oil-ring expanding of the piston head can take place without any hindrance, the piston head itself may be made resilient in that at the point of transition from the piston body to the piston head two opposite H-shaped transverse slits are arranged.

An embodiment of the invention is illustrated, by way of example, in the accompanying drawings in which

Fig. 1 shows the improved piston in longitudinal section.

Fig. 2 is a side elevation of Fig. 1, the piston rings being omitted.

Fig. 3 shows in longitudinal section, partly broken away, a piston of modified construction.

Fig. 4 shows in front elevation the open closure

of the protecting- and oil-ring for a piston of modified construction.

Fig. 5 is a cross-section on line V—V of Fig. 4.

Fig. 6 is a cross-section on line VI—VI of Fig. 4.

Fig. 7 is like Fig. 6, the two piston rings engaging the one in the other.

Fig. 8 shows the open closure viewed from the inner side of the ring.

Fig. 9 is a section through a piston equipped with protecting- and oil-ring according to Figs. 10 to 8.

Fig. 10 shows the spring-insert in top plan view.

Fig. 11 shows a portion of the spring-insert in section.

Fig. 12 is a cross-section through the spring-insert on line XII—XII of Fig. 10 on considerably enlarged scale.

Figs. 1 to 3 show the simplest form of construction of the improved piston, in which two piston rings *a* are preserved as well as the vertical slit *b* in the piston body. The arrangement of two parallel transverse slits *d*, *d'* in the piston head *c* is novel, said transverse slits being connected at the middle by vertical slits *d*² (Fig. 2). Owing to these slits also the piston head is made resilient.

The piston head *h* is set off, as shown in Fig. 1, and has an annular groove *f* for a protecting ring *g* which is constructed like a resilient piston ring. The edge of the piston head *h* may be formed by a ring *i* of harder material than that of the piston as shown in Fig. 3, whereby working of the ring *g* into the piston head when the motor is in operation is prevented. As this hard edge *i* does not touch the cylinder wall, seizing of the piston can not occur.

Oil channels *j* are formed in the piston head and end in the annular groove *f* which goes over into a bevelled edge *k*. The protecting ring *g* has an annular oil groove *m* which is connected by vertical grooves *n* with the annular oil channel *o* formed by the bevelled edge *k* (Fig. 3). The oil circulates in the grooves *m*, *n* and effects cooling of the upper part of the piston, as permanently fresh oil is admitted which cannot be converted into carbon.

In the piston shown in Fig. 9 the protecting ring *g* has two annular oil grooves *m* which are connected with the oil channel *o* by vertical grooves *n*. These vertical grooves may be mutually displaced. In this protecting ring the circulation of the oil in the grooves *m*, *n* is even better than at the piston shown in Figs. 1 and 3. The oil grooves *j* lead, in the piston shown in Fig. 9, to a ring channel formed in the piston

head in which an insert-spring p is located. The protecting ring g has on the inner side two annular grooves g' , g^2 (Fig. 7). The upper annular groove g' is cut into an extension l formed on one end of the ring and which on the inner side is of semi-circular shape (Fig. 5). By the groove g' two horizontal packing faces 2 , 3 are formed in the extension l . On the other end of the ring a cavity 4 of semi-circular cross-section is formed 10 as guide for the pin l (Fig. 6). In the ring end (Fig. 8) a recess 5 is thereby formed and further round packing faces 6 , 7 and two horizontal packing faces 8 which form extension of the faces 2 , 3 . The faces 2 , 3 and 8 bear from above and from 15 below against the upper ring flange h' of the piston head.

By the upper annular groove g' of the protecting ring not only a tight bearing of this ring against the flange h' of the piston head is formed, 20 but fire and gas are prevented from flowing through the closure, even when the two ends of ring g do not tightly join, as in this instance the gases from combustion impinge upon pin l which does not let them pass. The gases from combustion 25 can also not pass through the recess 5 , as the same is covered by the flange h' of the piston head and as further the recess 5 is not wider than the flange h' of the piston head so that the faces 2 , 3 and 8 effect a thorough packing even when 30 the ring g is expanded.

Between the protecting ring and the flange of the piston head sufficient clearance exists that an expansion of the piston head can take place without any forcible pressing of the protecting ring 35 against the cylinder wall. From the outer side the closure is kept tight by the cylinder wall (Fig. 9).

Whereas in the form of construction shown in Fig. 3 hammering of the protecting ring g is prevented by the hard outer rim i of the piston head, 40 a spring ring p which is undulated and composed of two parts is employed for the same purpose as shown in Fig. 9, each semi-ring being covered by two plates r , r' which are hook-shaped and grip 45 over the rear end of spring p , whereas the front ends are arc-shaped (Fig. 12) in order that the recess g^2 formed in the protecting ring may be easily slipped over the spring ring which then securely holds in position the protecting ring. 50 The oil channels j lead directly to the spring ring p and from the same to the oil channel o . Every half of the spring ring may be loosely connected with the plates r , r' by pins t fixed on the plate r and by sleeve s fixed on plate r' .

We claim:—

1. A piston for internal combustion engines, comprising in combination with the head having several annular grooves, the lowermost groove having a bevelled edge, a protecting ring in the piston head engaging in said annular grooves and having a plurality of oil grooves, the lower side of said protecting ring forming an oil channel with said bevelled edge of said lowermost groove, and vertical oil grooves in said protecting ring connecting said oil channel with said oil grooves in said protecting ring. 10

2. A piston as specified in claim 1, in which the protecting ring has at one of its ends a pin semicircular on the inner side, and at the other end a semicircular recess, said pin as well as said recess being intersected by the upper annular groove of the protecting ring. 15

3. A piston as specified in claim 1, in which the protecting ring has at one of its ends a pin semicircular on the inner side, and at the other end a semicircular recess, said pin as well as said recess being intersected by the upper annular groove of the protecting ring, said intersecting groove forming in the pin two horizontal packing faces 20 and in the recess two round packing faces and two horizontal packing faces for said edge of the piston head, so that the packing of said piston head edge remains uninterrupted by a shifting of said pin in its guide. 25

4. A piston as specified in claim 1, comprising in combination a set-off portion of the piston head, said protecting ring having a flange, and a ring of hard material in said set-off piston head said flange of said protecting ring bearing against 30 said hard ring.

5. A piston as specified in claim 1, comprising in combination with the protecting ring, a flange on said protecting ring, and an undulated spring-ring in one of the grooves in the piston head and bearing against said flange of said protecting ring. 40

6. A piston as specified in claim 1, comprising in combination with the protecting ring, a flange on said protecting ring, an undulated spring-ring in one of the grooves in the piston head and bearing 45 against said flange of said protecting ring, and two plates each curved downwards at the end and covering said spring-ring on both sides.

7. A piston as specified in claim 1, in which the piston head has two parallel transverse slits and vertical middle slits connecting said transverse slits. 50
